DISCHARGE VALVE ASSEMBLY FOR FUEL
INJECTOR PUMPSGeorge W. Baierlein, Springfield, Mass., assignor
to Niles-Bement-Pond Company, West Hart-
ford, Conn., a corporation of New JerseyOriginal application February 27, 1946, Serial No.
650,408. Divided and this application Febru-
ary 6, 1947, Serial No. 726,846.

2 Claims. (Cl. 103—154)

1

The present application is a division of my application Serial No. 650,408, filed February 27, 1946.

The present invention relates to fuel injection pumps for internal combustion engines. Certain of the features of the invention are of particular utility in connection with a pump for a multiple cylinder engine having a plurality of pump plungers, one for each cylinder. Other features of the invention are of especial utility in connection with an injection pump adapted for use on an aircraft engine, wherein light weight is very important.

An object of the present invention is to provide an improved pump barrel and discharge valve assembly for use in a pump of the type described.

Other objects and advantages of the present invention will become apparent from a consideration of the appended specification, claims and drawings, in which

The figure is a view, partly in cross-section, of a multiple plunger fuel injection pump and embodying my invention.

Referring now to the drawings, there is shown a pump mechanism consisting of a mounting plate 10, which is provided with a flange 12, having holes 14 bored through it to receive bolts (not shown) so that it may be mounted on a suitable pad provided on an internal combustion engine. A pump body 16 is attached, by any suitable means such as dowel studs, (not shown), to the mounting plate 10. A drive shaft 20 is carried in the plate 10 by a combined radial and thrust ball bearing 22 and by a needle bearing 24 in the body 16.

On the lower side, as it appears in the drawings, of the body 16, the shaft 20 carries, thru a combined thrust and radial bearing 26, a wobble plate 28. The wobble plate 28 actuates, thru mechanism to be described in detail below, a plurality of pump plungers 30, which reciprocate in barrels 32 received in bores 24 thru the housing 16. A cover 36 is provided for the pump. This cover is attached, by means of bolts and dowel pins (not shown) to the pump body 16.

The end of pump barrel 32 nearest the plate 10 is closed by a valve seat member 42. This seat member is provided with a passage thru its central portion, and a valve 44 engages the face of the seat member on the side opposite the barrel 32. A spring 46 biases the valve 44 to closed position. The spring 46 is held by a retainer 48 threaded into the plate 10. Washers 50 and 52 and a spacer 54 separate the rim of the retainer 48 from the rim of seat member 42. When the

2

retainer 48 is threaded in place, it holds the washers 50 and 52, the spacer 54, the seat member 42, and the barrel 32 in assembled relation, forcing a shoulder 56 on the barrel 32 up against a corresponding shoulder in the pump body 16. The spacer 52 is provided with lateral outlet passages 58, leading to a drilled passage 60 which opens into the bolt hole 14. From there the fuel discharged by the pump may be conveyed thru a hollow bolt, in a well-known manner, to one of the cylinders of the engine.

The outer surface of each of the barrels 32 is provided with a recess 33. A set screw 35, carried by the body 16 engages the recess 33 and holds the barrel against rotation in the body 16, so that the calibration of the pump cannot be disturbed by any change in the angular position of port 134.

The outer race of bearing 22 is press-fitted into the plate 10. The inner race is held against a shoulder on the shaft 20 by a lock nut 62 and a lock washer 64. It may be seen that the thrust forces on the bearing 22 are such as to tend to move the shaft 20 downwardly thru the plate 10. Therefore these thrust forces tend to hold the outer race of bearing 22 more firmly in its seat.

The inner race of bearing 26 is held in place against a shoulder on shaft 20 by a lock nut 66 and a lock washer 68. A timing disc 70 is clamped between the lock washer 68 and the inner race of bearing 26. The purpose of the timing disc 70 will be later described. The outer race of the bearing 26 is retained in the wobble plate 28 by a retaining ring 72, which may be of the well-known snap ring type.

Each of the plungers 30 is connected by means of a shear pin 74 to a push rod 76. The lower end of push rod 76 terminates in a ball 78. The wobble plate 28 is provided on its peripheral surface with a groove 80, wide and deep enough to receive the balls 78. The groove 80 separates an upper, as it appears in the drawing, flange 82 on the wobble plate from a lower flange 84. The upper flange 82 has its outer edge slotted, as at 86, so that the push rods 76 may be passed thru the slot during assembly. Each of the slots 86 opens into a generally circular aperture 88, which allows for the wobbling motion of the wobble plate 28 with respect to the push rods 76. Each of the balls 78 rides in a pair of upper and lower shoes 90 and 92, which are received with the ball in the groove 80. The upper shoe 90 is provided with a suitable central aperture to permit passage of the push rod 76 therethru. It may be

seen that as the shaft 20 rotates a wobbling motion is imparted to the plate 28 so that the plungers 30 and push rods 76 are sequentially reciprocated. It may also be seen that the thrust forces acting parallel to the shaft 20, due to the fluid pressures built up by the plungers, are all carried by the plungers 30, the associated structure which connects the plungers to the wobble plate, the wobble plate 28, and shaft 20 to the bearing 22 and the mounting plate 10. The body 16 is fixed at one end to the mounting plate 10. No other part of the body 16 is attached to any fixed part of the engine. Thrust forces reaching the plate 10 are not transmitted thru the body 16, because there can be no opposing reactive force. Hence 15 the body 16 cannot be stressed by such thrust forces. Therefore, it is possible to build the body 16 of a light, relatively weak metal such as aluminum, while the parts subject to stress are made of stronger metal, such as steel. In this way it has been found possible to substantially reduce the weight of the multiple pump unit. Where such a pump unit is intended for use in an aircraft, such a reduction in weight is tremendously important. It should be noted that the flange 82, which transmits thrust to the plungers on their intake strokes, is made lighter than the flange 84, which transmits thrust to the plungers on their pumping strokes. This difference in the thickness of the two flanges also contributes to the reduction of the weight of my pumping mechanism.

Each plunger 30, carries a sleeve 94, which includes a generally tubular portion 96. The portion 96 is slotted as shown at 98 from one side laterally across for a distance of more than half its diameter. The part of the sleeve 94 below the slot 98 is provided with a longitudinal slot as shown at 100, which separates that portion of sleeve 96 into two fingers which are provided at their free ends with lugs 106, 108 respectively. A tapered screw 110 is provided for joining the two lugs. It may be seen that upon tightening of the screw 110, lugs 106 and 108 are drawn together and the two fingers are tightly clamped on the surface of the push rod 76, so that the sleeve 94 and the push rod 76 and the plunger 30 rotate together. When the screw 110 is loosened, it is possible to rotate the push rod 76 within the sleeve 94 without rotating the latter. The sleeve 94 is provided with a pair of upwardly extending projections 112 which mate with corresponding projections 114 on a sleeve 116 which surrounds the barrel 32. The sleeve 116 carries a pinion gear 118 having teeth over at least a 90° sector thereof. All of the pinion gears 118 engage a central ring gear 120 carried on a projection hub portion of the pump body 16. The toothed portions of the pinion gears 118 all face inwardly so as to engage the ring gear 120.

One of the sleeves 116 is also provided, on the portion of its periphery nearest the outside of the casing, with a bevel gear sector 122. This engages with another bevel gear sector 124 carried by a control shaft 126 mounted in a suitable hub 128, which is carried by the pump body 16. Outside the body 16, the control shaft 126 is splined, as shown at 130 and thereby provided with means by which it may be rotated from the outside of the pump unit.

Each of the pump plungers is provided with a helical scroll 132 of generally conventional form, which cooperates with an inlet port 134. When the port 134 is closed by the scroll 132, then the plunger is actively pumping fuel thru the dis-

charge valve 44. Each plunger is also provided, below the scroll 132, with a circumferential groove 133. As soon as the port 134 is uncovered by the upper edge of groove 133, then the pressure ahead of the plunger is relieved and pumping ceases. By rotating the plunger on its own axis, the length of the period during which pumping takes place may be varied, thereby varying the fuel delivery per stroke of the pump plunger. By operation of the control shaft 126, all the plungers 5 may be simultaneously rotated. Rotation of control shaft 126 causes one pinion gear 118 to be rotated and this motion is transmitted thru the ring gear 120 to all the other pinion gears. If it is desired to adjust the delivery per stroke of one of the plungers, without affecting the others, it is only necessary to remove the cover 36 whereupon the clamping screws 110 associated with all the plungers become accessible.

10 The timing disc 10 cooperates with a timing pin 136 so that it is possible to determine the angular position of the pump shaft from the outside of the casing. The periphery of the disc 10 is slotted as shown at 138. The timing pin 136 is mounted in a cup 140 carried by the cover 36. A spring 142 in the cup 140 biases the pin to the position shown in the drawing where it does not engage the slot 138 or the timing disc 40. A cover 144 is provided for the outer end 20 of the timing pin so that it will not be accidentally pushed in while the pump is in operation. When it is desired to determine the angular position of shaft 20 for timing the pump to the engine, the cover 144 is removed and the pin 136 is depressed and held in. The shaft 20 may then be slowly rotated by hand until the pin is felt to drop into the slot 138. The slot 138 is located in the timing disc 10 so that its angular position corresponds to the end of delivery by 25 the pump plunger serving cylinder No. 1 of the engine.

30 The driving end of shaft 20 is driven thru an intermediate drive member 146, which corrects for misalignment between the pump shaft 20 and the engine drive shaft.

35 The shaft 126, outside the body 16 may be provided with a suitable pointer 150 cooperating with a scale 152, to indicate the pump delivery setting.

40 Fuel is supplied to the pump thru an inlet connection (not shown) which leads to a chamber 156 surrounding all the barrels 32 at a point near their inlet ports 134.

45 Oil is supplied under pressure through a connection (not shown) to the chamber 160 formed between the cover 156 and the pump body 116. The oil flows from the chamber 160 thru a check valve 162 and thence out thru the hollow center of the shaft 20. This lubricating system 50 is completely shown and claimed in the co-pending application of Milton E. Chandler, Serial No. 609,350, filed August 7, 1945, which has matured into U. S. Patent No. 2,423,373, of July 1, 1947, and forms no part of the present invention.

55 The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

60 I claim as my invention:
 1. Injector pump mechanism, comprising a body having a bore extending thru it and a

shoulder on said body within said bore, a barrel receivable in said bore and having a shoulder adapted to engage the shoulder in said bore, a recess in an external face of said barrel, a set screw insertable thru said body to engage said recess and hold said barrel against rotation, a plunger reciprocable in said barrel, a discharge valve seat member in said bore engaging the end of said barrel, a valve member engaging the face of said seat member opposite said barrel, hollow spacer means in each said bore engaging said seat and surrounding said valve, a spring retainer threadedly inserted in each said bore and engaging said spacer means to hold said spacer means, said seat member and said barrel in assembled relation, and a spring within said spacer and retained by said retainer and biasing said valve to closed position, said spacer being laterally apertured to permit outflow of fluid passed by said valve.

2. Injection pump mechanism, comprising a generally cylindrical housing including a mounting plate and a body attached to said plate, said body having a plurality of bores extending therethru from said plate parallel to the axis of said housing, a shoulder on said body within each said bore, said plate having a plurality of bores aligned with the bores in said body, a barrel receivable in each said bore and having a shoulder adapted to engage the shoulder in said bore, said barrels being longer than said body so as to extend within said plate when said shoulders are in engagement, a recess in an external face of each said barrel, a set screw insertable thru said

body to engage said recess and hold said barrel against rotation, a plunger reciprocable in each said barrel, a discharge valve seat member in each of said plate bores engaging the end of said barrel, a valve member engaging the face of said seat member opposite said barrel, hollow spacer means in each said plate bore engaging said seat and surrounding said valve, a spring retainer threadedly inserted in each said plate bore and engaging said spacer means to hold said spacer means, said seat member and said barrel in assembled relation, and a spring within said spacer and retained by said retainer and biasing said valve to closed position, said spacer and plate being laterally apertured to permit outflow of fluid passed by said valve.

GEORGE W. BAIERLEIN.
